M. D. KARLES.
PNEUMATIC TOOL.
APPLICATION FILED OCT. 6, 1919.

1,345,495.

Patented July 6, 1920.

UNITED STATES PATENT OFFICE.

MICHAEL D. KARLES, OF DELRAY, MICHIGAN.

PNEUMATIC TOOL.

1,345,495.

Specification of Letters Patent.

Patented July 6, 1920.

Application filed October 6, 1919. Serial No. 329,180.

To all whom it may concern:

Be it known that I, MICHAEL D. KARLES, a citizen of Poland, residing at Delray, in the county of Wayne and State of Michigan, have invented certain new and useful Improvements in Pneumatic Tools, of which the following is a specification, reference being had therein to the accompanying drawings.

10 In the operation of pneumatic hammers, riveters, and other tools wherein compressed air is utilized for imparting movement to a reciprocable tappet, ram, or piston, which impinges against a detachable tool, many 15 accidents have occurred due to the tool being discharged or projected from the hammer, resulting in injury to workmen and material. Various devices or attachments have been devised to prevent the accidental discharge of a tool, when knocked against a 20 piece of work, but such devices or attachments have been more or less defective for the purposes intended.

My invention aims to provide a simple, durable and inexpensive device that is applicable to various types of pneumatic hammers for preventing accidental discharge of a hammer head or other tool when the pneumatic hammer is placed in operation. The 25 device includes a novel clutch for holding a hammer head or tool in an operative position, and provision is made for shifting the clutch and holding it in a shifted position so that the hammer head or tool may be 30 safely removed.

My invention will be hereinafter specifically described and then claimed, and reference will now be had to the drawing, wherein—

40 Figure 1 is a side elevation of a pneumatic hammer or tool, partly broken away and partly in section, showing my improvement thereof;

Fig. 2 is an enlarged detail sectional view 45 of a portion of a pneumatic hammer, and

Fig. 3 is a cross sectional view taken on the line III—III of Fig. 2.

In the drawing, the reference numeral 1 denotes a barrel having the inner end there- 50 of provided with a handle 2 and in the outer end of said barrel is a tappet or ram 3 adapted to be successively struck, during the operation of the tool, by a piston or recipro- cable member in the barrel 1 and forming no

part of this invention other than contribut- 55 ing to a complete operative device.

The outer end of the barrel 1 is stepped to provide annular shoulders 4 and 5 and slid- able on the shoulder 5 is a cap 6 detachably connected to the inner end of the sleeve 7 60 having a conical shaped outer end or head 8 in which is placed a plurality of clutch jaws 9 adapted to engage in an annular groove or reduced portion 10 of a tool 11 mounted in the outer end of the tappet or ram 3, the tool 65 in this instance having a tang extending into the tappet or ram 3.

The clutch jaws 9 abut the end walls of the groove 10 and have beveled edges 12 en- 70 gaging beveled walls 13 of the conical head 8. The inner ends 14 of the clutch jaws 9 abut the outer end of the shoulder 5, and as shown in Fig. 2, the clutch jaws 9 positively anchor the tool 11 relative to the sleeve 7 75 and the outer end of the barrel 1.

Mounted on the outer end of the shoulder 5 is an annular abutment 15 and encircling the shoulder 5, between the cap 6 and the abutment 15 is a coiled spring 16 whose ex- 80 pansive force holds the sleeve 7 in a re- tracted position to retain the clutch jaws 9 in engagement with the tool 11.

Rotatable and reciprocable on the shoul- 85 der 4 is an annular hand piece 17 having opposed detachable studs 18 extending into spiral grooves 19 in said shoulder, and the hand piece 17 abuts the cap 6 so that when said hand piece is partially rotated the studs 18 and the grooves 19 cause the hand piece to ride outwardly on the shoulder 4 and 90 shift the cap 6 and the sleeve 7 against the expansive force of the spring 16. When the sleeve 7 is shifted outwardly the clutch jaws 9 are released and recede on beveled walls 20 of the conical head 8, so that the tool 11 may 95 be removed. The spiral grooves 19 have circumferential end portions so that the hand piece 17 may remain in an adjusted position.

The inner walls of the jaws 9 are provided 100 with grooves for a split expansive band spring 21 and the expansive force of the spring forces the jaws 9 outwardly, to re- tracted position.

It is thought that the utility of my device 105 will be apparent without further description, and while in the drawing there is illustrated a preferred embodiment of my invention, it

is to be understood that the structural elements are susceptible to such changes as fall within the scope of the appended claims.

What I claim is:—

- 5 1. The combination with a pneumatic tool barrel having a tappet therein and the outer end of said barrel provided with shoulders, of a cap slidable on one of said shoulders, a sleeve connected to said cap and having a conical head, clutch jaws in the head of said sleeve adapted to retain a tool in engagement with said tappet, a spring on said shoulder engaging said cap and adapted to hold said sleeve in a retracted position, and
- 10

means on another shoulder of said tool barrel adapted for shifting said sleeve to release said clutch jaws.

2. The combination set forth in claim 1 wherein said means is in the form of a rotatable and reciprocable hand piece having a stud and groove connection with the shoulder of said tool barrel.

In testimony whereof I affix my signature in the presence of two witnesses.

MICHAEL D. KARLES.
